UNITED STATES PATENT OFFICE.

ALBERT E. ABEL, OF WILKINSBURG, AND THOMAS H. DAVIES, OF BLACK LICK, PENNSYLVANIA, ASSIGNORS TO THE MARSHALL FOUNDRY COMPANY, OF PITTSBURGH, PENNSYLVANIA, A CORPORATION OF PENNSYLVANIA.

MOLDING APPARATUS.

1,233,949.

Specification of Letters Patent.

Patented July 17, 1917.

Application filed January 16, 1917. Serial No. 142,636.

To all whom it may concern:

Be it known that we, ALBERT E. ABEL and THOMAS H. DAVIES, citizens of the United States, residing at Wilkinsburg, county of Allegheny, and Black Lick, in the county of Indiana, and State of Pennsylvania, respectively, have invented certain new and useful Improvements in Molding Apparatus, of which the following is a specification.

10 Our invention consists of an improvement in molding apparatus and has in view to provide a removable core barrel adapted to be secured in position and easily and quickly removed from the bottom plate or drag of the mold, and to be centralized with relation thereto, in its position within the cheeks or flask. In the form shown, the invention is especially adapted to the casting of ingot molds.

20 Referring to the drawings:—

Figure 1 is a partial sectional view showing the base portion of the mold with the parts in operative position.

Fig. 2 is a cross section on the line II, II, 25 of Fig. 1.

Fig. 3 is a partial sectional detail view, similar to Fig. 1, showing a modified construction.

In the drawings, 2 is a central core barrel 30 of any suitable form, being generally rectangular in cross section, and in the illustration given, as adapted to the casting of an ingot mold.

The bottom plate 3 is provided with a 35 centrally arranged clearance cavity for the core barrel 2 within a surrounding inwardly extending abutment or flange 4 having a lower bearing face 5. Against this face, which may be sloping as shown, bears the laterally extending base flange 6 of the core barrel 2 by its upper engaging face. The advantage in making the contacting faces sloping, as shown, is that the core barrel 40 may be snugly seated and centralized in position, and will facilitate separation after the casting operation.

The under portion of the bottom plate 3 is provided with a depending base portion 7 having transverse tapered key-ways 8, 8, 50 at opposite sides, through which tapered keys 9 are driven inwardly, and which engage the bottom edge of the core barrel, as shown. By this means it is held tightly up

against flange 4 of the bottom plate in proper centralized position. 55

The surrounding cheek or flask 10 rests by its base upon the bottom plate, being provided with centralizing or locating holes and pins 11, or other suitable means.

In Fig. 3 we show a detail modification 60 of the mounting of the core barrel within the drag, in which the flange 4^a is provided with a flat horizontal face 5^a extending inwardly around the central clearance opening. The base flange 6^a of core barrel 2^a 65 is preferably provided with an upwardly turned bearing edge, while the drag 3^a is similarly provided with the base or lugs 7^a, keyways 8^a and keys 9^a.

In operation, the core barrel being secured in position by the keys, with the usual surrounding core box in place, sand 12 is packed between the core box and core barrel 2 and the core box removed. Sand 13 is rammed within the cheek or flask 10 in 75 connection with the usual pattern, and the entire surfaces of sand 12 and 13 and the exposed face of the drag are coated or blackened. Cheek 10 is then located in position on the drag as shown, and the mold 80 is placed in the oven for drying.

In casting, the molding or casting cavity 14 being filled in the usual way through runner 15, after sufficient cooling, keys 9 are withdrawn, when the central core barrel 2 85 may be forced downwardly through the bottom plate, effecting loosening and removal of the core barrel sand 12. The cheek may then be stripped from the bottom plate, releasing the casting, which is then 90 shaken out.

The used sand being thus removed from the core barrel, it is then lifted upwardly through the clearance opening in the bottom plate, these parts coming into proper 95 registering position, by their flange engagement, when the keys are again driven inwardly, and the core barrel and bottom plate are again ready for molding.

The advantages of the invention will be 100 readily appreciated by those familiar with the art.

The retaining engagement between the bottom plate and the core barrel, by their flange abutments, insures against dislocation or uncentering of the core barrel or its 105

upward movement by the buoyant action of the metal.

The barrel is thus positively held against movement in either direction, and all that is necessary to hold it in position is to locate the removable keys.

The feature of especial utility is in the mounting of the core barrel within the bottom plate so that it is held against upward movement and is removable downwardly therethrough. It will be understood that the construction or arrangement of the parts may be variously changed or modified by the skilled mechanic to adapt it to the making of various castings, or otherwise, within the scope of the following claims.

What we claim is:

1. In combination, a bottom plate having a central opening and an upwardly beveled 20 inwardly extending continuous flange, a core barrel having a continuous lateral flange adapted to engage said first named flange, said flanges being adapted to coöperate to center said core and to prevent upward movement, and removable locking keys mounted in the bottom plate and engaging underneath the base of said core barrel.
2. In combination, a bottom plate having

Copies of this patent may be obtained for five cents each, by addressing the "Commissioner of Patents, Washington, D. C."

a central opening, an upper inwardly extending continuous flange having a tapered 30 seating face, a core barrel having a lateral continuous flange having a co-acting face, a base flange depending from said plate having transverse tapered key ways therein, and removable locking keys mounted in said 35 key ways and engaging the under side of the base of the core barrel to lock said barrel in position.

3. In combination, a bottom plate having a central opening and an inwardly extending 40 continuous flange having an inwardly diverging tapered seating face, a core barrel having a continuous lateral flange having its upper face tapered to co-act with said flange on said bottom plate, said tapered 45 portions being adapted to center said core and prevent upward movement due to the buoyant action of the metal, and removable locking keys mounted in the bottom plate and engaging the under face of the base of 50 the core barrel to hold it in position.

In testimony whereof we hereunto affix our signatures.

ALBERT E. ABEL.
THOMAS H. DAVIES.
